UNITED STATES PATENT OFFICE

EARL F. CRAFT, OF ST. PAUL, MINNESOTA, ASSIGNOR TO BROWN & BIGELOW, OF
ST. PAUL, MINNESOTA, A CORPORATION OF MINNESOTA

DESIGN FOR A KEY CHAIN

Application filed September 21, 1927. Serial No. 23,484. Term of patent 3½ years.

To all whom it may concern:

Be it known that I, EARL F. CRAFT, a citizen of the United States, residing at St. Paul, in the county of Ramsey and State of Minnesota, have invented a new, original, and ornamental Design for Key Chains, of which the following is a specification, reference being had to the accompanying drawing, forming part thereof.

Figure 1 is a perspective view of a key chain showing my new design; and Figure 2 is a side elevation of the cylindrical element only.

I claim:

The ornamental design for a key chain as shown.

EARL F. CRAFT.
